[57] CLAIM

The ornamental design for a tamper resistant container lid, as shown and described.

DESCRIPTION

FIG. 1 is a top plan view of a tamper resistant container lid showing my new design;

FIG. 2 is a right side elevational view thereof;

FIG. 3 is a rear elevational view thereof;

FIG. 4 is a front elevational view thereof;

FIG. 5 is a bottom plan view thereof;

FIG. 6 is an enlarged sectional view thereof; taken on line 6—6 of FIG. 5;

FIG. 7 is a bottom plan view of an alternate embodiment of the design of FIG. 1;

FIG. 8 is an enlarged sectional view taken on line 8—8 of FIG. 7;

FIG. 9 is a top plan view of a second embodiment of the design of FIG. 1;

FIG. 10 is a right side elevational view of FIG. 9;

FIG. 11 is a front elevational view of FIG. 9;

FIG. 12 is a bottom plan view of FIG. 9;

FIG. 13 is an enlarged sectional view taken on line 13—13 of FIG. 12; and

FIG. 14 is an enlarged sectional view taken on line 14—14 of FIG. 12.
